UNITED STATES PATENT OFFICE.

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT.

STAPLING MACHINE.

Application filed May 21, 1924. Serial No. 714,805.

To all whom it may concern:

Be it known that I, FRIDOLIN POLZER, a citizen of the United States, residing at Norwalk, county of Fairfield, State of Connecticut, have invented a new and useful Stapling Machine, of which the following is a specification.

This invention relates to stapling machines, especially of the type adapted for use in setting staples to secure tags to boxes and the like. In the usual type of these machines there is a housing in which a plunger is mounted to slide, and the lower end of the plunger is arranged to coact with one end of a staple strip support to sever individual staples from a strip of connected staples and force the staples through the tag into the box to secure it thereto, suitable mechanism being provided which is operated by movements of the plunger to advance the staple strip with a step by step feeding movement to bring the individual staples into the proper position for severing and driving. At the outer end of the plunger is secured a head or cap to be struck by the hand for operating the plunger and setting the staples.

It has been found in practice that although this plunger and head was designed to be operated by a blow of the hand, the head being usually rounded and of considerable surface so as not to injure the hand, that where a large number of staples were driven the operator's would operate the machine to a large extent by hitting the head with a hammer or other instrument, and as they were not particular to hit the head in the center or on the axis of the plunger, but were just as liable to strike it off center or anywhere on the surface of the head, that a considerable strain was placed on the connection between the head and the plunger which soon separated the head from the plunger.

It is, therefore, an object of the present invention to provide means for absorbing a large portion of the force of this blow, especially one on the side of the head to prevent the breaking of the connection between the head and plunger.

It is also an object of the invention to provide an improved stop for limiting the movement of the plunger, which will equalize and distribute the force of this blow, or the pressure on the head, throughout the

under side of the head, and relieve the connection between the head and the plunger of the necessity of absorbing the force of the blow or pressure.

With the foregoing and other objects in view, I have devised the construction illustrated in the accompanying drawing forming a part of this specification, similar reference characters being employed throughout the various figures to indicate the corresponding elements. In this drawing,

Fig. 1 is a side elevation of the stapling machine in position for operation, the stop being shown in section and a portion of the housing being broken away to more clearly show the construction.

Fig. 2 is a front elevation looking from the left of Fig. 1.

Fig. 3 is a vertical section through the head and the stop means showing the plunger in its lowest position.

Fig. 4 is a section through the head showing the construction thereof.

In the drawing, 10 indicates in outline a portion of a box or other article to which the tag 11 is to be attached. Resting on this tag is shown the stapling machine comprising a housing 12 in which the various mechanisms are mounted for severing and driving the individual staples. This housing includes the usual handle 13 for holding in proper position. At the forward end of the housing are upright guide ways 14 for the plunger 15, the lower end of which coacts with the forward end of the slide 16 for supporting and guiding the usual strip of staples, not shown, to cut the individual staples from the strip, and then drive the severed staple. The plunger also has a laterally projecting lug 17 which engages a screw or rivet 18 to limit the upward movement of the plunger, and this lug is adapted to engage a finger 19 for operating the usual staple strip feeding mechanism, which is not shown, as it may be of any of the usual or desired constructions and forms no part of my present invention. I have also shown a staple straightening and holding device 20 which has two fingers 21 on opposite sides of the lug 17, which device moves with the plunger throughout part of its journey and passes between the prongs of the first and second staples on the strip to straighten the first staple on the strip should it be bent, or

to hold the staple against turning during the

severing operation. This device may or may not be employed, as desired. At its upper end this staple straightening and holding device has laterally projecting lugs 22 engaged on their under side by the upper end by a spring 23 embracing the plunger, and between the upper sides of these lugs and the under side of the cap or head 24 is a second spring 25 which is stronger than the lower spring 23, so that when the cap and plunger is depressed the holding device 20 moves downwardly with the plunger until the lower ends of the fingers 19 engage the top of the tag 11, when the movement of the device 20 will be arrested but the plunger will continue its downward movement to drive the staple.

The cap may be of any desired construction, but I have shown it as comprising an inner inverted cup member 26 having a central opening to receive the reduced portion 27 of the plunger, the cap resting upon the shoulder 28 formed by this reduced portion. The inner member may be secured to the plunger by any suitable means, as riveting over the end of the plunger or by welding, and is enclosed by a finishing member 29, preferably an inverted cup member of sheet metal spun over at its lower edge 30 about the edge of the inner member to secure it in position. This cap or operating head is preferably made of inverted cup shape as shown with a rounded upper surface to give a considerable surface to receive the blow of the hand in operation so as not to injure the hand, but it may, of course, be made of any shape found desirable or practical.

As pointed out above it has been found in practice that these devices are operated by hitting the top of the head with a hammer or other instrument, and it will be obvious that unless this blow is in the center of the top or along the axis of the plunger there will be a great tendency to turn the head on the plunger and break its connection with the plunger. To prevent the separation of the head from the plunger I provide a simple supporting member and stop between the head and the housing. In Figs.

1, 2 and 3 this stop and support comprises a cup member 31 embracing the plunger and the spring 23 and resting on a shoulder 32 on top of the housing, the end of the spring bearing on the inner wall of the cup. The side walls of this cup are substantially cylindrical leaving an annular upper end 33 which forms a seat for the head when the plunger is in its lower position, as shown in Fig. 3. It also provides a stop to limit the downward movement of the head and plunger. It will also be noted that the spring 23 tends to hold this member against the housing and at the same time tends to move the plunger to its upper position. In this form of device there is an opening 34 in the bottom of the cup for passage of the plunger and through which the plunger slides.

I prefer, instead of relying on the tag 11 as the means for stopping the movement of the straightening device, to so proportion the elements that the movement of the straightening device will be stopped at the proper time by engagement of lugs 22 with the inner curved wall 38 at the upper end of the stop member 31.

Having thus set forth the nature of my invention, what I claim is:

In a stapling machine, a housing, a plunger for driving the individual staples slidably mounted in said housing, a concavo-convex cap for direct manual operation secured to the upper end of the plunger for operating said plunger, a spring embracing the plunger and tending to move it to its upper position, and an independent cup shaped member having an opening in its bottom wall for passage of the plunger and tubular side walls to embrace said spring, the lower end of said cup being arranged to engage the housing and the upper end arranged to engage the under side of the cap at a substantial distance from its center to limit the movement of the plunger and support the cap to prevent breaking of the connection between the cap and plunger.

In testimony whereof I affix my signature.

FRIDOLIN POLZER.
